(57) CLAIM

The ornamental design for a “solar battery charger with adjustable meter and light”, as shown and described.

DESCRIPTION

FIG. 1 is a front view of a “solar battery charger with adjustable meter and light”, incorporating my new design;

FIG. 2 is a rear view thereof;

FIG. 3 is a left side thereof;

FIG. 4 is a right side view thereof;

FIG. 5 is a top view thereof;

FIG. 6 is a bottom view thereof;

FIG. 7 is a front, bottom, left side perspective view thereof;

FIG. 8 is a front, bottom, left side perspective view thereof in a first alternative configuration;

FIG. 9 is a rear, bottom, left side perspective view thereof in a second alternative configuration;

FIG. 10 is a front, top perspective view thereof in a third alternative configuration; and,

FIG. 11 is a front, bottom, left side perspective view thereof in an opened configuration.
